UNITED STATES PATENT OFFICE.

EUGENE J. RAY, OF BEVERLY, MASSACHUSETTS, ASSIGNOR TO UNITED SHOE MANUFACTURING COMPANY, OF PATERSON, NEW JERSEY, A CORPORATION OF NEW JERSEY.

SEWING-MACHINE.

1,246,320.

Specification of Letters Patent. Patented Nov. 13, 1917.

Application filed December 27, 1915. Serial No. 68,756.

To all whom it may concern:

Be it known that I, EUGENE J. RAY, a citizen of the United States, residing at Beverly, in the county of Essex and State of Massachusetts, have invented certain new and useful Improvements in Sewing-Machines; and I do hereby declare the following to be a full, clear, and exact description of the invention, such as will enable others skilled in the art to which it appertains to make and use the same.

The invention relates to sewing machines, and more particularly to machines for forming overseam stitches about the edge of a buttonhole.

Sewing machines of this type are usually provided with an upper needle and co-operating loop taking devices below the work for taking a loop from the upper needle during each reciprocation. At the completion of a sewing operation the sewing mechanism is arrested with the upper needle in retracted position, and with the last loop taken from the needle still held by the loop taking devices. When the needle thread is severed above the work, either automatically or by the operator, the waste end leads down through the last needle hole about the loop taking devices to the previous stitch, and as the work is spaced or removed, this waste end is drawn down through the last needle hole by reason of its engagement with the loop taking devices, and remains as a comparatively long thrum end on the under side of the work.

On certain classes of work these thrum ends on the under side of the work are seriously objectionable, and it is the object of the present invention to prevent their production. To this end the invention contemplates the provision in a sewing machine having an upper needle and under-loop taking devices, of means for preventing the taking of the loop from the upper needle during the final reciprocation of the needle, so that at the completion of the sewing the needle thread will lead from the needle down through the last needle hole and directly to the previous stitch. The severed end of the needle thread will not therefore be drawn down through the needle hole to the under side of the work when the work is

removed or spaced. The thread may be severed close to the upper side of the work, and the end will be retained in the last needle hole. It is preferred to prevent the taking of the loop from the needle by a thread takeup which is inactive until the final reciprocation of the needle, and then pulls on the thread as the needle starts upward, and thus keeps the thread out of the path of the loop taking devices. This construction is not essential to the broader features of the invention, however.

The invention will be readily understood from an inspection of the accompanying drawings, and the following detailed description of the mechanism illustrated therein.

In the drawings, Figure 1 is a side elevation, partly in section, showing so much of a buttonhole sewing machine as is necessary to illustrate the application of the present invention thereto; Fig. 2 is a front elevation, partly in section, on line 2—2, Fig. 6; Figs. 3, 4 and 5 are details showing the upper needle and thread in different positions during the last reciprocation of the needle; Fig. 6 is a partial plan view of the machine; and Fig. 7 is a partial sectional view showing the parts in a different position from that shown in Fig. 2; and Fig. 8 is a detailed section on line 8—8, Fig. 2.

In the drawings the invention is shown as embodied in a buttonhole making machine having in general the construction and mode of operation of the machine shown and described in Patent No. 1,063,880, dated June 3, 1913. In this machine the stitch forming mechanism comprises an upper needle 2, an under needle 4, and a looper 6, which takes a loop from the upper needle below the work and holds it in position for the passage of the under needle therethrough. The upper needle is carried by a needle bar 8 which is mounted to reciprocate in a rotary head 10, and the under needle and looper are mounted in a rotary turret 12. The work is held in position over the throat plate 14 by a work clamp comprising the under jaws 16 carried by the work supporting plates 18, and the upper jaws 20 carried by the arms 22 which are pivoted to blocks mounted on the work sup-

porting plates. The work supporting plates are mounted on a carrier 24 which is moved to bring the work from cutting to sewing position, and to feed the work during the sewing, as described in the patent above referred to.

The upper needle thread leads from the tension device 26 through the thread guides 28, and through a guide 30 in the end of a 10 takeup arm 32, and then to the upper end of the hollow needle bar 8, down through which it passes to the light tension device 34 and to the eye of the upper needle. During the sewing of the buttonhole the takeup arm 15 32 remains in the inactive position indicated in dotted lines in Fig. 6, and during each reciprocation of the upper needle the needle casts out a loop, indicated in dotted lines in Fig. 4, which is taken by the looper 6 and 20 held in position for the passage of the under needle therethrough. During the last reciprocation of the needle at the end of the sewing operation, the takeup arm 32 is swung into the full line position of Fig. 6 during 25 the upward movement of the needle, and keeps the thread taut between the previous stitch and the eye of the needle, as indicated in full lines in Fig. 4, so that the point of the looper does not pass between the 30 thread and the needle. The taking of the loop by the looper is thus prevented during the last reciprocation of the needle, and when the sewing mechanism is arrested at the completion of the sewing, the thread will 35 lead from the previous stitch along the under surface of the work and up through the last needle hole to the eye of the needle, as indicated in Fig. 5. The needle thread may be severed close to the work either 40 automatically or by the operator, and the severed end will be retained in the last needle hole when the work is spaced or removed, and the production of thrum ends on the lower side of the work will thus be avoided. 45 The means shown for operating the takeup arm 32 in the manner above described comprises a lever 36 provided at its free end with a gear segment 38 which engages a gear segment 40 secured to the lower end of the 50 rock shaft 42, to the upper end of which the takeup arm is secured. The lever 36 is mounted on a vertical pivot stud 44 which is forced downward by a spring 46, and the lower end of which is supported upon a controlling bar 48. The lever is provided with a depending pin 50 which is engaged by a 55 cam 52 on the driving shaft 54 for the sewing mechanism during the last reciprocation of the needle. During the sewing of the 60 buttonhole the lower end of the pivot stud for the lever 36 rests on the surface 56 at the end of the controller bar 48, and the lever 36 is held in raised position, as indicated in Fig. 7, so that the pin 56 is out of the

path of the cam 52. During the sewing, 65 therefore, the takeup arm 32 remains in the dotted line position of Fig. 6, being held in position by the spring 58. The controller bar 48 is connected through the rack teeth 60 and the segment 62 with the rock shaft 70 64 which carries the stop arm 66 forming a part of the mechanism for stopping the shaft 54 at the completion of the sewing operation. During the sewing the stop arm and rock shaft are swung into the dotted 75 line position of Fig. 6, and remain in this position until the sewing mechanism is to be arrested, when they are swung into the full line position of Fig. 6 by a cam 68 on the cam gear 70, which engages an arm 72 on the rock shaft. When the stop arm and rock shaft have swung into the full line position, the controller bar 48 is moved into the position indicated in Fig. 2, so that the recess 74 in the upper face of the bar registers with 80 the pivot stud of the lever 36, thus allowing the lever to move down into the position indicated in Fig. 2, and bringing the pin 50 on the lever into the path of the cam 52. During the last revolution of the shaft 54 the cam 52 therefore acts to swing the takeup lever from dotted to full line position of 85 Fig. 6, and causes it to pull on the thread during the last upward stroke of the needle and thus prevent the taking of the loop by the looper, as above described. When the stop arm and rock shaft are swung into inactive position in starting the driving shaft 54 for the sewing mechanism, the controller 90 bar 48 is returned to the position indicated in Fig. 7, thus disengaging the pin on the lever 36 from the cam 52, so that the takeup arm 32 may return to dotted line position, 95 preparatory to its next thread pulling movement. 100

While it is preferred to employ the specific construction and arrangements of parts shown and described, in embodying the invention in the machine of the patent above referred to, it will be understood that this 110 arrangement is not essential, but may be varied or modified as found desirable or best suited to the construction of machine in which it is to be embodied.

Having explained the nature and object 115 of the invention, and specifically described one form of mechanism in which it may be embodied, what is claimed is:—

1. A sewing machine, having, in combination, sewing mechanism comprising a needle and co-operating loop-taking devices, means normally inactive for preventing the taking of the loop from the needle, a normally disconnected actuator for the preventing means, and a controller for determining the 120 stitch forming cycle in which the actuator shall actuate said preventing means.

2. A sewing machine, having, in combina-

tion, sewing mechanism comprising a needle and coöperating loop-taking devices, a takeup, a normally disconnected actuator timed to actuate the takeup during the up-stroke of the needle, and controller means for connecting the actuator and takeup during a predetermined stitch forming cycle.

3. A sewing machine, having, in combina-

tion, sewing mechanism, a takeup, a cam rotating in time with the sewing mechanism, 10 and a controller for connecting the cam to actuate the takeup during the final reciprocation of the needle at the completion of the sewing.
